FISHING LURE

Donald A. Newman, Jr., 2209 Woodland Ave.,
Augusta, Ga. 30904

Filed Mar. 19, 1973, Ser. No. 342,418

Term of patent 14 years

Int. Cl. D22—05

U.S. Cl. D22—27

FIG. 1

FIG. 2

FIG. 3

FIG. 4

FIG. 1 is a side elevational view of the fishing lure of my design;

FIG. 2 is a left end view of the fishing lure shown in FIG. 1;

FIG. 3 is a right end view; and

FIG. 4 is a cross-sectional view taken along the line 4—4 of FIG. 1.

The opposite side, top and bottom are a continuation of the side shown.

The broken lines are for illustrative purposes only.

I claim:

The ornamental design for a fishing lure, substantially as shown and described.
